AIR CHARGING CONTROL

Ambrose E. Le Van, Sellersville, Pa., assignor to
 American Machine and Metals, Inc., New York,
 N. Y., a corporation of Delaware

Application April 12, 1946, Serial No. 661,899

15 Claims. (Cl. 103—5)

1

This invention relates to a jet pump system wherein a pump delivers liquid from a well into a pressure liquid storage tank, and, more particularly, to a device for controlling the air contents in the tank.

In pressure liquid storage tanks only part of the space in the tank is taken up by liquid, whereas the upper portion of the tank contains compressed air. While the liquid is standing in the container it absorbs gradually more and more of the air on top of the liquid, and when liquid is withdrawn from the tank, it carries with it some of the air so absorbed.

Various devices permitting a small amount of air together with the water drawn from the well to be drawn into the suction side of a pump are known and one such device is shown in the Patent 2,291,746 granted to R. N. Nelson et al. When a pump is first started up, the suction is abnormally high to provide the force necessary to put the column of water in the well and the piping in motion and this high suction may result in drawing in air at such a rapid rate that the pump suction is so reduced that the pump fails to fill itself with water drawn up from the well and becomes air-bound.

The invention provides for the first time for the admission of air to the suction side of the pump only if air is needed in the tank and then only after the suction pressure has reached normal values.

It is an object of this invention to provide a device capable of controlling the quantity of air in the pressure liquid storage tank in a manner to replenish the air contents in the tank by means of air drawn into the system in response to the difference between atmospheric pressure and a variable suction pressure created by the pump delivering the liquid into the tank.

A further object of the invention is to provide a device which controls the amount of air added to a closed tank for storing liquid under pressure by permitting air to be drawn into the system by the liquid flowing from the tank through a Venturi passage to the pump inlet, the Venturi passage being normally closed by a valve, said valve being opened only when the level of liquid in the storage tank rises above a pre-set point and at the same time, the pressure differential between the inlet of the pump and the atmosphere is less than a pre-set value.

A further object of the invention is to provide a device for controlling the air contents in a pressure liquid storage tank, wherein air is drawn into the system by means of liquid passing

through a Venturi passage controlled by a valve whenever, and as long as, said valve is open.

It is another object of the invention to provide in a jet pump system, wherein a pump delivers liquid from a well into a pressure liquid storage tank, a by-pass leading from the tank to the suction side of the pump for the admission of finely dispersed air particles into the liquid system, said by-pass including a Venturi section wherein the static liquid pressure of the liquid flowing therethrough is reduced to a subatmospheric value to suck in atmospheric air when a valve controlling this Venturi section is open, said valve being openable only when unlocked from a mechanism responsive to variations of the liquid level in the tank and, if so preconditioned for an opening movement, will be opened when the suction pressure of the pump is or falls below a pre-set value.

A further object of the invention is to provide in a device for controlling the air contents in a pressure liquid storage tank, wherein air is drawn into the system by means of a liquid passing through a Venturi passage controlled by a valve, a diaphragm for closing said valve responsive to the difference of atmospheric pressure and the suction pressure created by the pump and a spring capable of opening the valve against the diaphragm pressure when said suction pressure is less than a pre-set amount.

Still another object of the invention is to operatively connect the valve controlling the aforementioned Venturi passage with the aforementioned means responsive to changes in the liquid level in the tank by means of an element which is movable relative to the valve in the direction of the axis of the latter and which carries a locking member extending into the path of said valve.

Other objects and features of the invention will appear as the description proceeds, reference being had to the accompanying drawing, which shows the invention applied to a pressure water storage tank such as used in individual systems where well water is drawn up from the well by an ejector placed near the bottom of the well, and in which:

Fig. 1 shows in a diagrammatic elevational view, partly in section, one form of a jet pump system; and

Fig. 2, at a larger scale, a vertical section of the air controlling device proper.

In the drawing, the numeral 10 denotes a closed storage water tank, the lower portion 11 of which contains water and the upper portion 12 air. The water level varies during use, a desired maximum

level being indicated at 13 and the minimum level at 14. A float 15 follows the variations of the liquid level for operating a valve 16 situated in a body 17 which is screwed into the side wall of the tank 10. The water level in the tank stands always, even at the minimum level 14, above the valve 16.

The valve 16 controls a passage 18 in the body 17. The passage 18 is open towards the tank 10 and has a Venturi section 19 behind which said valve 16 is located. The Venturi section 19 leads to a chamber 20 which communicates with the suction side of a pump 22, preferably a rotary or centrifugal pump, through a conduit 21.

Carried by the body 17 is a pivot 23 for a bell crank lever 24, whose one end is rigidly connected with the float 15 in the tank 10 by means of a bent rod 25 and whose other end is fastened to a wire 26.

Leading into the Venturi section 19 of the liquid passage 18 is an air channel 27 which communicates with the outside atmosphere and in which an air-check valve 28, such as a snifter valve, is provided.

When the level of the water in the tank 10 is low, such as at 14, the float 15 sinks from the position shown in Fig. 1 to a lower position corresponding to that level 14 and, by means of the connection 25, 24, pulls the wire 26 to the extreme left. The wire 26 extends into the bore of the valve 16 and is headed therein by means of a head 26' so that the valve 16 may move axially relative to the wire 26 unless the latter is pulled in the manner just described to the left, indicating a low water level in the tank. If so pulled to the left, it will keep the valve 16 locked in its closing position so that no water can flow through the passage 18 and the Venturi throat 19 and no air is drawn into said throat through the air channel 27.

The chamber 20 is closed at one side by a diaphragm 29 held in place by a plug 30 which is screwed into the body 17 and has a central hole 31 connecting the space behind the diaphragm 29 with the atmosphere. Thus the diaphragm 29 is subjected at one side, the rear side, to atmospheric pressure and at its front side to the suction pressure existing in the chamber 20 due to the connection of the latter with the suction side of the pump 22. With the difference of these two pressures the diaphragm 29 bears against the rear part of the valve 16 either directly or through the intermediary of a spring plate 32 attached to the valve 16 near the rear end thereof. The spring plate 32 is acted upon by a spring 33 which tends to expand and thereby to open the valve 16 whereas the diaphragm 29 tends to close it. The spring 33 is so selected that it will be able to overcome the closing effect of the diaphragm 29 upon the valve 16 when the above mentioned difference between atmospheric pressure and the suction pressure acting upon the diaphragm from within the chamber 20 is below a pre-set value.

34 denotes a well in which the water is at a certain level, such as the level 35. A Venturi-type ejector 36 is placed near the bottom of the well 34 with its suction pipe 37 immersed in the pool 40 of the well. The jet nozzle 38 of the ejector is connected to the pressure side of the pump 22 by means of a conduit 39, whereas its delivery nozzle 41 is connected to the suction side of the pump 22 by means of the suction pipe 42. From the discharge or pressure side of the pump there leads a conduit 43 to the bottom of the tank 10.

Water may be withdrawn from the tank 10 through a pipe line 44 on opening a spigot 45.

When the pump 22 is running, it forces some water down the pipe 39 from which this water discharges through the nozzle 38 of the ejector 36. In well-known manner the jet delivered by the nozzle 38 brings up additional water from the pool 40. The combined water stream passes the pump 22 and while part of this water goes down again to the ejector 36 another part is discharged via the conduit 43 into the tank 10, compressing the air in the space 12 of the tank. When a desired air pressure has been reached, the motor driving the pump is turned off, either by hand, or more generally by an automatic pressure operated switch (not shown).

Assuming that the water in the tank 10 stands as low as the level 14, then the float 15 holds the bell crank lever 24 and the wire 26 with its head 26' in the position shown in Fig. 2, keeping the passage 18 in the body 17 closed by the valve 16. Therefore, no water passes through the Venturi throat 19 of the passage 18 and, consequently, there is no suction action upon the air channel 27. Regardless of the pressure (positive or negative) which may exist in the chamber 20, the valve 16 is held locked in its closed position and cannot move as long as there is no release by the head 26' of the wire 26.

When the water level in the tank rises, the float 15 rises with it, turning the bell crank lever 24 in clockwise direction and moving, thereby, the wire 26 with its head 26' to the right. The extent of this movement of the wire 26 depends on how high the level in the tank rises. When the water in the tank reaches the level 13, the head 26' of the wire 26 is moved to its extreme right position, which permits the valve 16 to open fully. The movement of the wire 26 to the right does not entail in itself an opening movement of the valve 16. Such movement of the wire 26 merely unlocks, or preconditions, the valve 16 for an opening movement, but whether or not the valve actually opens depends upon the pressure existing or developing in the chamber 20. This, in turn, depends on the suction effect produced by the pump 22 with the suction side of which the chamber 20 is connected. When the pump 22 starts up, it develops a very strong suction, which may be on the order of 15 or 20 feet of water. Thus, during this starting period, the atmospheric pressure acting through the opening 31 in the plug 30 upon the right hand side of the diaphragm 29, which tends to keep the valve 16 closed, is supported by the strong suction in the chamber 20. The spring 33 is not strong enough to overcome the sum of these two closing forces, and the valve 16 remains on its seat. There is thus no water flowing through the passage 18, 19 and no air is admitted to the system, in spite of the fact that the wire 26 has been moved to the right where it would not obstruct opening of the valve 16, if the latter were to open. For the reason given, however, the valve 16 remains closed so that no air is admitted to the system at this time, that is, when the pump is exerting an excessive suction upon the chamber 20. Admission of air at this time would involve the danger of so large an amount of air entering the upstarting pump that the suction thereof might be broken.

When the starting period of the pump 22 is ended and the latter assumes or approaches normal operation, its suction pressure diminishes to a value which ordinarily is not much different from the atmospheric pressure. When the alge-

braic difference of the atmospheric pressure acting upon the rear side of the diaphragm 29 and the suction pressure acting upon the other side of the diaphragm reaches a value below a predetermined positive value, the force of the spring 23 acting upon the spring plate 32 attached to the valve 16 becomes sufficient to overcome the flexure of the diaphragm 29 and thereby to open the valve 16. Now, under the static pressure of the liquid in the tank 10 and the suction in chamber 20, liquid flows from the tank through the passage 18, 19. In the Venturi section 19 of this passage 18, 19 the static pressure of the liquid is reduced to a subatmospheric value. Due to the subatmospheric pressure in the Venturi throat 19 air is drawn through the air passage 27 past the check valve 28 and into said Venturi throat 19 where it mixes with the liquid stream so as to become finely dispersed therein. The air-laden water passes through the chamber 20 and the conduits 21 and 42 into the pump 22. From here part of the air-laden liquid goes directly through the conduit 43 into the tank 10, whereas another part is forced down through the conduit 39 to the ejector 36 where it meets the water coming from the well 34 and then is drawn up again into the suction side of the pump 22. In this manner a by-pass is provided for the admission of finely dispersed air particles into the liquid system. Upon reaching the tank 10 the air rises to the surface of the liquid in the tank in the form of bubbles and thus replenishes the air contents in the tank and raises the air pressure therein to the required value.

It will be observed that air is drawn through the passage 27 into the liquid by-pass whenever, and as long as, the valve 16 is open. The rate of flow of the air will depend largely upon the magnitude of the suction created in the Venturi throat 19 by the liquid passing therethrough, which suction in turn will be the greater the wider the valve 16 opens. Within the limits of the suction pressure of the pump 22 between which the valve 16 will open at all, the valve opens the less the higher the suction pressure of the pump 22 is. Therefore, air will always be drawn into the liquid system at a properly controlled rate so as, on the one hand, not to endanger the proper function of the pump 22 and, on the other hand, to secure the admittance of an ample amount of air even though the suction effect of the pump may be relatively very low. Contrariwise, when the suction effect of the pump is extraordinarily high, such as during a starting-up period of the pump, the admission of air through the by-pass is cut off just as completely as when the valve 16 is held locked in its closing position by the head 26 of the wire 26 due to a low water level in the tank.

While the pump 22 is working, the water rising in the tank 10 compresses the air on top of the water. When the permitted maximum level 13 is reached, the pump is shut off. This may be done, as has been mentioned before, by an automatic pressure-operated switch. If now, while the pump is not supplying any more water into the tank, water is withdrawn from the tank 10, such as by opening the spigot 45, the level of the liquid in the tank falls and the air on top of the liquid expands, losing in pressure. When this decreasing pressure reaches a certain low value, the automatic pressure-operated switch will turn on the pump again. To give a practical example: the automatic switch may be adjusted so that it shuts off the pump when the pressure in the tank

reaches 40 pounds per square inch, and starts the pump up again when the pressure drops to 20 pounds per square inch.

The pump being restarted, refilling of the tank takes place. If no air would be added to the air present above the liquid in the tank, refilling of the tank up to the level at which the withdrawal of water started would not restore the air pressure which existed in the tank when the spigot 45 was opened, on account of the fact that the water withdrawn from the tank carried with it air absorbed from the space 12 in the tank 11. The air drawn in through the air passage 27, regulated in the manner described, supplies just enough additional air to the system to compensate for the air loss occurring when water is withdrawn from the tank.

While I have shown and described one particular embodiment of the invention in one particular application, it will be understood that the invention is applicable to the control of the air contents of other pressure tanks than water storage tanks and to other pump systems than the one shown, and further that the particular embodiment shown in the drawing has been given by way of example only, since many changes, rearrangements, and modifications of the parts shown and described hereinbefore may be made without departing from the spirit of the invention or from the scope of the appended claims.

What I claim is:

1. In combination, a body having a chamber, suction-creating means connected to said chamber, a Venturi passage in said body one end of the passage leading to the chamber while the other end is connected to a supply of liquid, a valve adapted to prevent the flow of liquid from said passage into said chamber, a flexible diaphragm forming one wall of said chamber so as to be exposed on one side to the action of said suction creating means, and bearing against said valve under the action of atmospheric pressure to which it is exposed on its other side, a spring tending to open said valve, said spring being strong enough to overcome the flexure of said diaphragm and thereby to open said valve only if the difference between the two pressures acting upon the two sides of said diaphragm is below a predetermined value, an air channel communicating with the atmosphere and opening into said Venturi passage, and an air valve in said air channel for admitting air to said Venturi passage when and as long as said liquid valve is open.

2. In combination, a liquid supply, suction creating means, a body, a chamber in said body connected to said suction creating means, a Venturi passage in said body communicating with said liquid supply and emptying into said chamber, a liquid valve between said Venturi passage and said chamber, a flexible diaphragm forming one wall of said chamber so as to be exposed on one side to the action of said suction creating means whereas its other side is exposed to atmospheric pressure, a spring tending to open said valve, said spring extending between a stationary abutment provided in said chamber and a spring plate attached to said valve so as to move together with said plate, said diaphragm bearing against at least one of the two parts valve and spring plate, said spring being strong enough to overcome the flexure of said diaphragm and thereby to open said valve only if the difference between the two pressures acting upon the two sides of said diaphragm is below a predetermined value, an air channel in permanent communica-

tion with the outside atmosphere and opening into said Venturi passage, and an air valve in said air channel for admitting air to said Venturi passage when and as long as said liquid valve is open.

3. In combination, a body having an inlet for liquid of higher than atmospheric pressure, a discharge outlet, a suction creating pump attached to the discharge outlet, a passage for liquid extending from said inlet to said outlet, a Venturi section in said passage wherein the static pressure of the liquid flowing through the passage is less than atmospheric, a valve beyond said Venturi section adapted to close the flow through said passage, a diaphragm tending to close said valve responsive to the difference between atmospheric pressure and the suction pressure existing at said outlet, a spring capable of opening the valve against the diaphragm pressure when said suction pressure is less than a preset amount, and an air connection from the atmosphere to said Venturi section permitting air to be drawn into the liquid flowing through said body.

4. In a jet pump system, in combination, a well, an ejector in the well, a pump at the top of the well, a conduit leading from the ejector to the suction side of the pump, a conduit leading from the discharge side of the pump to the ejector, a conduit leading from the discharge side of the pump, a receiving tank into which said conduit leading from the pump discharges liquid, a by-pass designed to admit finely dispersed air particles into the liquid system and leading from said tank to said suction side of said pump, a Venturi section in said by-pass wherein the static liquid pressure of the liquid flowing through the by-pass is subatmospheric, a valve beyond said Venturi section adapted to close the flow through said by-pass, a diaphragm tending to close said valve responsive to the difference between atmospheric pressure and the suction pressure at the pump inlet, a spring capable of opening the valve against the diaphragm pressure when the suction is less than a pre-set amount, and an air connection from the atmosphere to said Venturi section permitting air to be drawn into the liquid flowing through said by-pass.

5. In a jet pump system, in combination, a well, an ejector in the well, a pump at the top of the well, a conduit leading from the ejector to the suction side of the pump, a conduit leading from the discharge side of the pump to the ejector, a conduit leading from the discharge side of the pump, a receiving tank into which said conduit leading from the pump discharges liquid, a by-pass designed to admit finely dispersed air particles into the liquid system and leading from said tank to said suction side of said pump, a Venturi section in said by-pass wherein the static liquid pressure of the liquid flowing through the by-pass is subatmospheric, a valve beyond said Venturi section adapted to close the flow through said by-pass, a diaphragm tending to close said valve responsive to the difference between atmospheric pressure and the suction pressure at the pump inlet, a spring capable of opening the valve against the diaphragm pressure when the suction is less than a pre-set amount, an air connection from the atmosphere to said Venturi section permitting air to be drawn into the liquid flowing through said by-pass, and means responsive to changes in the liquid level in said tank operatively connected with said valve for keeping said valve locked in its closing position when said liquid level is at or below a given height and

unlocking it for movement into its open position when said lever is above said given height.

6. An apparatus for controlling the air contents in a storage tank into which liquid is delivered by a pump, said apparatus comprising a storage tank, a body having a passage communicating with the liquid space in said tank, a valve for opening and closing said passage, means for admitting air to said passage whenever said valve is open, means responsive to changes in the liquid level in said tank including an elongated element movable relative to said valve in the direction of the axis of the latter, said elongated element carrying a locking member extending into the path of said valve for keeping said valve locked in its closed position when said liquid level is at or below a given height and unlocking it for movement into its open position when said level is above said given height, a pump for feeding liquid to the tank, and means responsive to changes in the suction developed by said pump determining when said valve, when unlocked by said liquid level responsive means for movement into its open position, will actually be so moved.

7. In combination, a body having an inlet for liquid of higher than atmospheric pressure, a discharge outlet, a suction-creating pump attached to the discharge outlet, a passage for liquid extending from said inlet to said outlet, a Venturi section in said passage wherein the static pressure of the liquid flowing through the passage is less than atmospheric, a valve beyond said Venturi section adapted to close the flow through said passage, a diaphragm tending to close said valve responsive to the difference between atmospheric pressure and the suction pressure existing at said outlet, a spring capable of opening the valve against the diaphragm pressure when said suction is less than a pre-set amount, an air connection from the atmosphere to said Venturi section permitting air to be drawn into the liquid flowing through said body, and an elongated element movable relative to said valve in the direction of the axis of the latter between two end positions, said elongated element carrying a locking member extending into the path of said valve so as to keep, when in its one end position, said valve locked in its closing position and to unlock said valve for movement into its open position when in a position other than said one end position.

8. In a jet pump system, in combination, a well, an ejector in the well, a pump at the top of the well, a conduit leading from the ejector to the suction side of the pump, a conduit leading from the discharge side of the pump to the ejector, a conduit leading from the discharge side of the pump, a receiving tank into which said conduit leading from the pump discharges liquid, a by-pass designed to admit finely dispersed air particles into the liquid system and leading from said tank to said suction side of said pump, a Venturi section in said by-pass wherein the static liquid pressure of the liquid flowing through the by-pass is subatmospheric, a valve beyond said Venturi section adapted to close the flow through said by-pass, a diaphragm tending to close said valve responsive to the difference between atmospheric pressure and the suction pressure at the pump inlet, a spring capable of opening the valve against the diaphragm pressure when the suction is less than a pre-set amount, an air connection from the atmosphere to said Venturi section permitting air to be drawn into the liquid flowing through said by-pass, and means responsive to changes in the liquid level in said tank operatively connected with said valve for keeping said valve locked in its closing position when said liquid level is at or below a given height and

sive to changes in the liquid level in said tank including an elongated element movable relative to said valve in the direction of the axis of the latter, said elongated element carrying a locking member extending into the path of said valve for keeping said valve locked in its closing position when said liquid level is at or below a given height and unlocking it for movement into its open position when said level is above said given height.

9. In a water system, in combination, a conduit having an inlet which is below the level of a body of water, an ejector nozzle in said conduit tending to draw water up through said inlet, a pump whose suction side is connected to said conduit and whose discharge side is connected to said ejector, a closed tank, a conduit leading from the discharge side of the pump into said closed tank, a water delivery pipe extending out from the lower part of said tank, an apparatus permitting air to flow from the atmosphere to the suction side of the pump, a valve in said apparatus controlling the flow of air through said apparatus, means responsive to the level of the water in the tank adapted to actuate said valve, other means responsive to the amount of the suction pressure at the inlet side of the pump, both adapted to actuate said valve to closed position.

10. In a water system, in combination, a conduit having an inlet extending below the level of a body of water, an ejector nozzle in said conduit tending to draw water up through said inlet, a pump whose suction side is connected to said conduit and whose discharge side is connected to said ejector, a closed tank, a conduit leading from the discharge side of the pump into said closed tank, a water delivery pipe extending out from the lower part of said tank, means for feeding air to the tank, comprising a conduit extending from the tank to the suction side of the pump, a venturi in said conduit wherein the pressure is sub-atmospheric even though the pressure at the pump inlet be positive, an air inlet to said venturi, a valve in said conduit adapted to prevent the flow of water and air through the conduit, means responsive to the level of the water in the tank and other means responsive to the suction pressure at the inlet side of said pump, both adapted to close said valve.

11. In combination, a tank, a body adapted to be fitted into an opening in said tank, a pipe connection to that part of the body extending outside of the tank, a passage having a Venturi section extending through the body from within the tank to the pipe connection, an air inlet leading to the Venturi section, a valve adapted to close the passage, means responsive to the level of the water in the tank, means responsive to the pressure of the fluid in the pipe connection, said last two means cooperating to operate said valve to permit the flow of air into the pipe connection only when the water level in the tank is above a set value and the fluid pressure in the connection exceeds a set value.

12. In a water supply system, in combination, a feed pump, a receiving tank having air under pressure in a space above the water surface, means adapted to admit air to the suction side of said pump only when the air space in the tank has decreased below a preset volume and the suction pressure at the pump entrance does not exceed a given value, comprising, a body adapted to be fastened with its inner end projecting into an opening in the wall of said tank, a recess extending into said body from its outer end, a dia-

phragm closing off the recess to form a chamber, a passage extending from the chamber through the body into the tank, a Venturi contraction in said passage, an inlet admitting air to said passage at the Venturi contraction, a connection from the chamber to the suction side of said pump enabling it to draw some water from the tank through the venturi and thereby to draw in air which is mixed with the water before reaching the pump, a valve in the chamber adapted to be moved inward into position to close the flow through the passage by said diaphragm, a calibrated spring resisting the inward distortion of the diaphragm by suction in the chamber.

13. In a water supply system, in combination, a feed pump, a receiving tank having air under pressure in a space above the water surface, means adapted to admit air to the suction side of said pump only when the air space in the tank has decreased below a preset volume and the suction pressure at the pump entrance does not exceed a given value, comprising, a body adapted to be fastened with its inner end projecting into an opening in the wall of said tank, a recess extending into said body from its outer end, a diaphragm closing off the recess to form a chamber, a passage extending from the chamber through the body into the tank, a Venturi contraction in said passage, an inlet admitting air to said passage at the Venturi contraction, a connection from the chamber to the suction side of said pump enabling it to draw some water from the tank through the venturi and thereby to draw in air which is mixed with the water before reaching the pump, a valve in the chamber adapted to be moved inward into position to close the flow through the passage by said diaphragm, a calibrated spring resisting the inward distortion of the diaphragm by suction in the chamber.

14. In a water supply system, in combination, a feed pump, a receiving tank having air under pressure in a space above the water surface, means adapted to admit air to the suction side of said pump only when the air space in the tank has decreased below a preset volume and the suction pressure at the pump entrance does not exceed a given value, comprising, a body adapted to be fastened with its inner end projecting into an opening in the wall of said tank, a recess extending into said body from its outer end, a diaphragm closing off the recess to form a chamber, a passage extending from the chamber through the body into the tank, a Venturi contraction in said passage, an inlet admitting air to said passage at the Venturi contraction, a connection from the chamber to the suction side of said pump enabling it to draw water from the tank through the venturi and thereby to draw in air which is mixed with water before reaching the pump, a valve in the chamber adapted to be moved into position to close the flow through the passage, a float in the tank connected to said valve to hold said valve closed unless the water in the tank stands above a given level, a connection between the diaphragm and the valve adapted to close the valve when the diaphragm flexes inward, a calibrated spring resisting the inward distortion of the diaphragm by the suction created by the pump.

15. An apparatus for controlling the volume of air in a storage tank to which liquid is delivered

11

by a pump, comprising, a storage tank, a pump connected to the storage tank, a body adapted to be fixed in the wall of said tank, a chamber in the body, a passage in said body connecting said chamber with one end of the body, a valve adapted to open and close the passage, a connection from the chamber to the suction side of said pump, a Venturi connection in said passage, a connection to the atmosphere for drawing air into said passage at the venturi whenever the valve is opened and liquid flows through the passage, means responsive to changes of the liquid level in said tank including an element movable relative to the valve in the direction of the latter, said element carrying a locking member extending into the path of the valve to keep the valve locked when said liquid level is at or below a given height and unlocking it for movement to

10 open position when said level is above said given height, and means for locking said valve when unlocked by the liquid level responsive means in response to the suction in the chamber created by said pump so as to keep said valve seated when said suction in the chamber exceeds a predetermined value and to open it when said suction is below said value.
